THOMAS EDGAR AUD, OF HERNDON, VIRGINIA.

CLOSURE FOR CONTAINERS.

Application filed April 15, 1927. Serial No. 184,163.

This invention relates to a closure for containers, particularly those, such as air, gas or liquid holding containers, or other similar containers, having a mouth or opening required to be sealed tight against the exit or entrance of fluids.

In the use of various kinds of containers which should be proof against the escape or admission of air, gas, water or other fluid, 10 it is desirable to have a seal or closure for the mouth or entrance and exit opening which may be closed or sealed in an hermetically tight manner. In the case, for example, of the gas bags or ballonets of airships and other containers it is also desirable 15 to have a closure which, while being absolutely leak-proof when in sealed condition, will permit of a rapid and convenient unsealing action for inspection or repairs of the 20 bag, or for other purposes.

The object of my invention is to provide a closure which fulfills these requirements and which may be constructed and applied for use at a comparatively low cost.

25 In the accompanying drawing,—

Figure 1 is a fragmentary plan view of a container, such as a gas bag, having a mouth or opening provided with a closure constructed in accordance with my invention, one of the sealing strips being represented as partly severed from a wall of the bag and turned backward to better disclose the construction.

Figure 2 is a plan view of the bag with 35 the closure members in position to seal the bag.

Figure 3 is a section taken substantially on line 3—3 of Figure 2.

Figure 4 is a cross-sectional view through 40 the sealed closure on an enlarged scale.

Figure 5 is a view also on an enlarged scale looking toward one end of the closure.

Figure 6 is a sectional view on a greatly 45 enlarged scale taken substantially on line 6—6 of Figure 5.

Figure 7 is a longitudinal section through the runner.

Referring now more particularly to the drawings, 1 designates the body of a container, having at one end a mouth or opening 2 which is shown as provided with means, constructed in accordance with my invention, for sealing it in an hermetically tight manner. The container here shown may be 50 a gas bag or ballonet, such as employed in

aircraft or for other purposes, or it may be a bag for holding any kind of fluid for any purpose. The bag may be constructed of rubber, rubberized cloth or other fluid impermeable material. The closure may be 60 made, however, of any suitable material, and of any form or shape, or for any purpose, and I therefore do not limit the invention in any of these respects.

The walls of the container at the mouth 65 or opening 2 are provided with closure members or strips 3 and 4, which are preferably made of elastic or semi-elastic material. They may be made, for example, of partially vulcanized rubber, or rubber and fabric, or 70 rubber and any other suitable more or less flexible or resilient reinforcing means. These strips are designed to be moved apart for a mouth opening action and to be brought together for a mouth sealing or 75 closing action, and said strips are provided with opposed contact faces 5 and 6 adapted to closely engage each other for the sealing action.

As shown, one of the strips, as the strip 80 3, is provided with a longitudinally extending groove or recess 7 opening through its sealing face 5 and which is preferably of hexagonal or other angular form in cross-section, its side adjacent the face 5 being 85 cut away and shaped to form a flaring entrance 8 to the groove 7 which opens directly through the face 5. The other strip 4 is provided with a rib or tongue 9 for interlocking and sealing engagement with the 90 groove or recess 7, and which is of a cross-sectional form conforming to that of said groove or recess. The strip 3 is made sufficiently elastic so that its portions lying at 95 opposite sides of and forming the walls of the groove 7 may have relative outward and inward movements, to expand and contract the entrance 8 of the groove. The groove 7 and rib or tongue 9 are adapted to be interlocked by movement of the strips toward 100 one another under pressure applied to said strips, and are adapted to be released by a movement of the strips in an outward direction or away from each other. The rib or tongue 9 while made of more or less 105 elastic material should have a certain degree of rigidity in order to maintain the interlocking connection when the parts are interlocked. For this purpose I preferably provide a reinforcement 10 for the rib, which 110

may be of T-shape, as shown, and molded in the strip and rib at the time the same are formed.

For the purpose of moving the strips toward one another and compressing them for the interlocking action, a slide or runner 11 is provided. This may be made of metal or other suitable material and comprises a body which is open at each end and in general 10 of U-shaped cross-section, said body comprising what may, for convenience, be termed top and bottom walls 12 and 13 and an outer side wall 14, the inner side wall being cut away or provided with a slot 15 formed by flanges 16 projecting inwardly from the walls 12 and 13. This slide or runner is designed to embrace the strips 3 and 4 with its top and bottom walls 12 and 13 lying parallel with the top and bottom 15 surfaces of said strips, the wall 14 bearing against the outer sides of the strips and the flanges 16 engaging the inner sides of the strips to hold the runner from lateral displacement, the slot 15 providing for the passage 20 of the adjacent portions of the walls of the bag and admitting of the movement of the runner without interference therefrom. Carried by the top and bottom portions of the runner are bearing rollers 17 which extend 25 cross-wise of the runner and project into the channel thereof. These rollers are adapted to serve as anti-friction cam or wedge surfaces to bear against the top and bottom faces of the strips 3 and 4 to force 30 said strips together for the sealing and locking action in the movement of the runner in one direction along said strips. The rollers are suitably positioned upon the runner so as to reduce the depth of the runner at one 35 point, so that, assuming the strips to be separated, a movement of the runner along the strips will cause, through the action of the rollers, a pressure of the strips together, by which means the tongue 9 will be forced into 40 interlocking engagement with the groove 7, the walls of the mouth portion 8 of the groove expanding sufficiently to admit the rib. When the rib is engaged with the groove 7 the faces 5 and 6 of the strips 45 will lie in contact and will be held locked against separation by the engagement between the rib and groove, the rib projecting across and additionally sealing the joint between the sealing faces and the angular formation 50 of the rib and groove providing additional sealing surfaces to effectually prevent the outward passage of fluid from the container through the sealed closure. The slide 55 11 is provided with a knob or handle 18 for moving it along the strips.

For the purpose of effecting a close clamping engagement between the walls of the groove 7 and the rib 9, and to prevent any possibility of the separation of the strips or 60 relaxation of the engaging surfaces suffi-

ciently to prevent leakage of fluid under pressure, I provide means for compressing the walls of the undercut portions of the groove against the sides of the undercut portion of the rib. To this end the strip 70 3 is provided with a channel 19 opening at its base through the face 5 and extending the length of the strip in close proximity to the inner wall of the undercut portion of the groove 7. A spreader 20 is movable 75 in the channel 19 and is preferably longitudinally tapered or wedge-shaped so that, at any point along the channel which it occupies, the elastic portion of the strip 3 between the groove 7 and channel 19 forming 80 the wall of one side of the undercut portion of the groove will be forced toward the outer wall of the groove; thus contracting said groove in an obvious manner. The spreader 20 is connected at its forward 85 end by a link or other connection 21 with an arm 22 carried by the runner 11 and arranged to lie in advance of the runner in its direction of sealing movement. The spreader will occupy that portion of the 90 channel in that portion of the strip 3 embraced by the runner, and its tapered or wedge formation is such as to effect a contraction of the groove after the strips have been brought together and the tongue and 95 groove interlocked. It will be observed that the outer wall of the groove lying opposite the spreader 20 will be backed by the wall 14 of the runner, and that consequently no outward lateral deflection of said 100 wall or rib 9 can occur during the groove contracting action of the spreader, so that a positive wedging engagement between the walls of the groove and rib will be instituted. A comparatively stiff cord or cable 105 23 is attached to the spreader 20 for convenience in retracting it.

In practice, while the runner may be of materially less length than the length of the sealing strips, the spreader 20 and cord 110 23 are jointly of a length greater than the length of the strips, whereby the channel 19 will be filled by the spreader and cord from end to end thereof when the runner is in its advance position in its sealing action and the free end of the cord will project sufficiently beyond the opposite ends of the strips to allow it to be gripped and pulled for a spreader retracting action. When the parts are in sealing position as 115 120 just described the spreader and cable will cooperate with the outer wall of the runner to hold the groove contracted, as will be readily understood. When the container is sealed, therefore, the spreader 20 will operate as a supplemental locking device to hold the groove contracted and obviate any liability of separation or displacement from sealing position of the sealing members, so that the closure will be kept hermetically 125 130 sealed.

sealed against the escape of pressure from the container. It is, of course, to be understood that the closure may be employed as an excluder instead of a retainer, that is to say, may be used upon any kind of a receptacle for preventing entrance of water or other fluid thereto, instead of preventing escape of the fluid from the receptacle.

In the use of the device, assuming that the runner is out of engagement with or displaced at one extreme end of the strips, so that the mouth of the bag can be completely or partly opened as desired, the movement of the runner toward the opposite ends of the strip, which may be effected by the operator pushing on the handle 18, will cause those portions of the strips successively engaged by the rollers 17 to be forced together for the sealing and locking action. It will be observed that the arm 22 connected with the spreader 20 lies in advance of the runner and in the space between the strips as the runner is moved along, whereby the spreader 20 will be drawn along with the runner for the supplemental locking action without any interference by the arm 22 with the strip closing action. At the end of the closing movement of the runner the runner 20 will be in the advanced position shown in Figure 2 and the arm 22 will lie beyond the adjacent side of the bag. With the runner in this position the spreader 20 and cable 23 will occupy the channel 19 throughout its length, thus maintaining the locking connection against any pressure which may fall upon it. The cord or cable 23 is adapted to be engaged to permit the spreader 20 to be pulled rearwardly on the reverse or unsealing motion of the runner. In this reverse movement the pressure of the spreader on the walls of the groove is gradually removed allowing the arm 22 to enter between the meeting faces of the strips to slightly spread them apart, whereupon the free ends of the strips may be engaged and pulled apart to disconnect the groove and rib and permit the strips to be entirely separated for a full unclosing or unsealing action.

The walls 12 and 13 of the runner may be provided, as clearly shown in Figure 7, with wedge or cam surfaces 24 for the purpose of pressing the closure strips 3 and 4 together, the rollers 17, however, extending peripherally inwardly beyond such surfaces so as to ensure an easy movement of the runner over the strips; the rollers acting to press the strips to a greater degree together for the interlocking action between the rib and groove. I may, however, dispense entirely with the cam or wedge surfaces 24 and use the rollers only. In practice, the strips 3 and 4 may be wholly free from connection with each other throughout their

lengths, adapting the mouth of the bag to 65 be opened or closed by movements in which the walls of the bags to which the strips are attached are movable to equal degrees, from side to side thereof, toward and from each other. The strips may, however, be united 70 at one end, beyond the adjacent end of the mouth, in which event the walls of the bag will open and close in V-fashion. These and other changes or modifications falling within the spirit and scope of the invention, 75 as defined in the appended claims may be made, as conditions or circumstances may require in the use of the invention upon different types of containers or receptacles.

Having thus fully described my invention, 80 I claim:

1. A container having a mouth or opening, sealing strips attached to and extending along the margins of the mouth or opening, said strips being made of more or less elastic material and having sealing faces, the sealing face of one strip being provided with a groove and the sealing face of the other strip having a tongue to interlock with said groove, a runner movable along the strips 85 for forcing them together and causing the rib to interlock with the groove, and means movable with the runner for coaction therewith to compress the walls of the groove 90 against the rib. 95

2. A container having a mouth or opening, sealing strips attached to and extending along the margins of the mouth or opening, said strips having sealing faces, one of said strips being provided with a groove having 100 a contracted entrance opening through its sealing face and the other strip having a tongue to interlock with said groove, a runner movable along the strips to force the same together and cause the tongue to interlock with the groove, and a spreader movable with the runner and coacting therewith to compress the walls of the groove 105 against the tongue.

3. A container having a mouth or opening, sealing strips attached to and extending along the margins of the mouth or opening, said strips being made of more or less elastic material and provided with sealing faces, one strip having a groove opening through 110 its sealing face and the other strip having a tongue projecting from its sealing face to interlock with said groove, a runner movable along the strips for pressing them together and effecting a sealing and locking action between them, and means movable with the runner and coacting therewith for compressing the walls of the groove against the sides of the tongue. 115 120

4. A container having a mouth or opening, sealing strips of more or less flexible material attached to and extending along the margins of the mouth or opening, said

- strips having sealing faces, the face of one strip being provided with a groove having a contracted mouth and the sealing face of the other strip having a tongue with a contracted base portion, a runner movable along said strips and provided with means for forcing the strips together and causing the tongue to interlock with the groove, the strip having the groove being provided with a longitudinal channel parallel with one wall of the groove, a spreader attached to the runner and movable in said channel and coacting with the runner to force the walls of the mouth of the groove into sealing contact with the surfaces of the contracted base portion of the rib, and a channel filling and spreader retracting cable attached to said spreader.
5. A container having a mouth or opening, sealing strips attached to and extending along the margins of the mouth or opening, interengaging means carried by said strips for interlocking them and forming an interbridging sealing connection when the strips are brought together, a runner movable along the strips for bringing them into locking and sealing engagement, and means movable with the runner and coacting therewith to hold said locking and sealing means in tightly compressed condition. 20 25 30

In testimony whereof I affix my signature.
THOMAS EDGAR AUD.
